UNITED STATES PATENT OFFICE.

WILLIAM P. VARNEY, OF CHICAGO, ILLINOIS, ASSIGNOR TO HYDRAULIC PRESS BRICK COMPANY, OF ST. LOUIS, MISSOURI, A CORPORATION OF MISSOURI.

DESIGN FOR A BRICK OR SIMILAR ARTICLE.

48,536.

Specification for Design.

Patented Feb. 8, 1916.

Application filed November 17, 1914. Serial No. 872,670. Term of patent 14 years.

To all whom it may concern:

Be it known that I, WILLIAM P. VARNEY, a citizen of the United States, residing at Chicago, in the county of Cook and State of Illinois, have invented a new, original, and ornametal Design for Bricks or Similar Articles, of which the following is a specification, reference being had to the accompanying drawing, forming part thereof.

The figure is a perspective view of a brick, showing my new design.

The design consists in an irregular surface resembling heavy, long napped, tufted, cloth produced by disposing clay particles upon the faces of the brick.

I claim—

The ornamental design for a brick or similar article as shown and described.

WILLIAM P. VARNEY.
